UNITED STATES PATENT OFFICE.

IRVING FLORMAN, OF NEW YORK, N. Y.

DESIGN FOR A BODY FOR A PORTABLE CIGARETTE AND CIGAR LIGHTER.

Application filed February 21, 1928. Serial No. 25,510. Term of patent 3½ years.

To all whom it may concern:

Be it known that I, IRVING FLORMAN, a citizen of the United States, residing at New York, in the county of New York and State of New York, have invented a new, original, and ornamental Design for a Body for a Portable Cigarette and Cigar Lighter, of which the following is a specification, reference being had to the accompanying drawing, forming part thereof.

The figure is a side view of a lighter body showing my new design, the lighter mechanism being shown by dotted lines.

I claim:

The ornamental design for a body for a portable cigarette and cigar lighter, as shown and described.

IRVING FLORMAN.
